Inventor

George H. Kidney

United States Patent Office.

GEORGE H. KIDNEY, OF CLEVELAND, OHIO.

Letters Patent No. 70,096, dated October 22, 1867.

IMPROVED WASHING MACHINE.

The Schedule referred to in these Letters Patent and making part of the same.

TO ALL WHOM IT MAY CONCERN:

Be it known that I, GEORGE H. KIDNEY, of Cleveland, in the county of Cuyahoga, and State of Ohio, have invented certain new and useful improvements in Washing Machines; and I do hereby declare that the following is a full and complete description of the construction and operation of the same, reference being had to the accompanying drawings, making a part of this specification, in which—

Figure 1 is a top view of the machine.

Figure 2 is a vertical section.

Figure 3 is a detached view.

Like letters of reference refer to like parts in the views.

In the above figures, A represents the case or tub of the machine, which is of an oblong square form, and supported on legs A', the bottom being inclined from each end toward the centre, as shown in fig. 2. Secured near the centre of the case, on a shaft, a, is the open cylinder B, which consists of the two end pieces b, connected together by means of the ribs or bars B', extending from one to the other of the said head-pieces b. Under this cylinder is hung the apron C, a top view of which, when detached, is shown in fig. 3. Secured in the sides of the tub is the bar or shaft D, to which one end of the apron is hung, by means of the ropes or chains I, as hereafter shown. In the opposite end of the tub, extending from side to side, the same as the bar D, is a shaft, on which are placed the pulleys E. The apron C referred to is composed of blocks c, of the form represented, which are connected together by means of cords I, on which they are strung in the order shown in fig. 3, the cords passing through the bar D, to which the apron is hung, the ends of the cords passing over the pulleys E, above referred to, to which ends are attached the weights F, the purpose of which is to draw the apron close up against the clothes, thus pressing them firmly against the bars or rubbers of the cylinder. If desired, springs may be used in place of the weights above described. In the cylinder B one of the ribs is made adjustable, one end slipping under the loop d, and the other end secured, when desired, by means of the hook e, fig. 1.

When the clothes are to be washed they are secured to the cylinder by means of this adjustable rib, which is raised up, and one end of the piece to be washed placed under it. The rib is then put in place and secured as stated. This is so that the clothes can be rubbed on both sides. By turning the cylinder the cloth is brought between the apron and ribs of said cylinder, and thoroughly cleaned; then, by turning the cylinder in the opposite direction; the other side of the cloth is rubbed. The apron being hung as stated, and composed of the blocks strung on the cords as described, renders it adjustable. If the clothes become packed between the apron and cylinder the pressure on the apron will raise the weights, and thus allow the apron to be depressed. Thus any cloth, large or small, can be washed easily, and the apron adapt itself to the variable thicknesses or size of said cloth. If large the weights will be raised by the pressure on the apron, and thus give room between the cylinder and apron for the clothes. By means of the blocks of this apron being strung on the cords as stated, the apron is rendered flexible, and any part will be depressed, where the thickness of the clothes between said apron and cylinder may require.

What I claim as my improvement, and desire to secure by Letters Patent, is—

1. The combination of the cords I with the blocks c, when constructed and arranged in relation to each other so as to be interwoven or interlocking, forming a continuous or entire connected apron, substantially as and for the purpose set forth.
2. The arrangement of the apron C, in combination with the cylinder B, in the manner and for the purpose substantially as specified.
